ABSTRACT OF THE DISCLOSURE

In the particular embodiment of the invention described herein, a rolling mill includes hydraulic pistons applying a force tending to urge the backup roll bearing chocks apart in parallel with the separating force exerted by the material being rolled. A force detector interposed between the chocks and the mill frame detects the total roll separating force and another gage responds to the pressure applied to the hydraulic actuators. A control system responsive to these components causes the pressure applied to the hydraulic pistons to vary in the opposite manner from the total force thereby tending to maintain the separating force constant.

The present invention relates to an arrangement for shaping metals by rolling, and more particularly, to a novel and improved arrangement for producing a constant thickness output product from a rolling mill stand irrespective of thickness, temperature, or metallurgical properties of the incoming product or strip.

A conventional rolling mill stand generally includes two work rolls which, by rotating in opposite directions, seize or grasp the metal and draw it through the rolls reducing its thickness and increasing its length. It also includes a mill housing which constrains the separating forces imparted to the rolls by the metal being rolled, and a means of adjusting the separation of the work rolls within the mill housing. In commercial usage, various types of mill stands are employed which utilize different numbers and combinations of rolls depending upon the type of metal, width of the product being rolled, amount of reduction required, and other factors such as quantity of production. Before the rolling process commences, the two work rolls are adjusted so that their separation or gap is equal to the thickness of the desired output product less the stretching and bending of the mill stand which result from the reaction to the roll separating forces developed during the rolling process.

After the no-load adjustment or preset of the roll separation, if there were no variations in thickness, temperature, or metallurgical properties of the incoming metal, strip, or sheet, then the thickness of the output product would be uniform. Inasmuch as the properties of the incoming product do vary and cause changes in the stand separating forces, variations in the thickness of the output product result.

The above-mentioned problem is, of course, not new in the art and various attempts have been made to compensate for the characteristics of the incoming product to thereby maintain a uniform output thickness.

The most common approach has been to attempt to provide an automatic means of adjusting the roll separation during the rolling process to compensate for the effects of stand stretch introduced by variations in the incoming product. One common arrangement used is to employ an adjustment screw, the tightening or loosening of which may adjust the separation between the work rolls. Adjustment screws are generally controlled in their oper-

2

ation by screw drive motors which are supplemented by sophisticated motor controls. These motor controls may, in turn, be controlled by a plurality of gages measuring the various physical characteristics of the product entering or leaving the mill stand. Objections to such a system are generally raised on the grounds of high costs and substantial adjustment time lags due to the inertia of the screw mechanism and of the motor controlling the screws.

10 Adjustment means are also known which act on the rolls independently of the adjustment screws, such as hydraulic actuation of the nut associated with the adjustment screws, the introduction of wedge actuators between the adjustment screws and the roll chocks, and the substitution of hydraulic rams for the adjustment screws to adjust roll separation. While these adjustment means, in some instances, overcome the objections to the use of motor controlled adjustment screws, they must be powerful enough to act against the total roll separating force 20 and are objectionable in many instances because of their cost or difficulty in execution.

Accordingly, it is an object of the present invention to provide a new and improved system for maintaining the working roll separation during the operation of a rolling mill which overcomes the above-mentioned disadvantages of the prior art.

Another object of the invention is to provide a new and improved system which responds rapidly enough to permit complete automatic gage regulation of the material 30 being rolled in a single mill stand.

A further object of the invention is to provide an adjustment system which is simple and efficient in operation, may be installed easily in conventional rolling mill stands, and is capable of providing a highly accurate adjustment to maintain the roll separation gap.

Another object of the present invention is to provide a new and improved method for maintaining in uniform fashion the output product of a rolling mill.

An additional object of this invention is to provide an 40 arrangement wherein relatively high force actuator devices are provided which tend to urge the rolls apart thus coacting with the separating force imparted by the metal being rolled in opposition to the constraining forces of the mill housing. By being responsive to a control signal, 45 the actuators can rapidly compensate for variations in the incoming product to maintain a uniform thickness in the output product of the mill stand.

These and other objects of the invention are obtained by providing, in a rolling mill having a fixed frame and a 50 pair of work rolls, one of which may be adjustable to the other to vary the roll separation, a plurality of actuator devices acting in parallel with the roll separating forces imparted by the metal being rolled and in opposition to the constraining action of the mill stand. By 55 varying in a controlled manner the forces applied by these actuators, the forces applied by the work rolls to the product being rolled can be adjusted so as to maintain a uniform output product.

More particularly, the no-load roll gap is preset with 60 the adjusting screws to provide a greater than normal reduction in the thickness of a product of predetermined properties, and thereafter the actuators are adjusted to stretch the mill stand and thereby achieve normal reduction of such a rolled product. Adjustment of the actuators 65 therefore need only be made about this level, and inasmuch as the actuator forces act in parallel with the mill stand separating forces produced by the strip passing the work rolls, the maximum actuator force need only be as great as the maximum force perturbation range required to correct for variations in the incoming product.

It has been found that the adjustment force can be obtained from the solution of the following equation:

$$\Delta F_C = (\Delta F_C - \Delta F) \left(1 + \frac{M_F}{M_R} \right)$$

wherein M_F and M_R are the elastic moduli of the mill stand, neglecting the effect of the rolls, and mill rolls respectively, and wherein ΔF is the variation or differential in force constrained in the mill stand housing, and ΔF_C is the variation or differential in force applied by the actuators.

The solution of the above equation may be accomplished by utilizing a load cell for sensing the variations in the force (F), constrained in the mill stand housing, and applying a signal representative thereof to a system which solves the above equation and adjusts the actuators accordingly.

Further objects and advantages of the invention will be apparent from a reading of the following description in conjunction with the accompanying drawings, in which:

FIG. 1 is a side view of a typical rolling mill stand provided with control actuators and with a representative system for controlling the actuators; and

FIG. 2 is a partially broken-away view taken along line 2-2 of FIG. 1.

In a typical four-high rolling mill, wherein the present invention may be practiced, a rolling mill stand 10 includes a rigid housing 11 in which is mounted a roll assembly having a plurality of rolls mounted about substantially parallel axes including a lower backup roll 12, a lower working roll 13, an upper working roll 14, and an upper backup roll 15, all of the usual type. Within each side of the housing 11 the lower backup roll 12 is supported in a lower bearing chock 16, and each side of the lower working roll 13 is supported and guided in a smaller bearing chock (not shown) which in a conventional manner fits into a corresponding opening in the chock 16. Similarly, at each end of the housing 11, the upper backup roll 15 is supported in a bearing chock 18 and each side of the upper working roll 14 is guided by a small bearing chock (not shown) which is received in a corresponding opening in a chock 18, each of the backup roll bearing chocks being mounted for vertical sliding motion in the usual manner so as to permit adjustment of the working roll separation.

As in conventional mill stands, an electric screwdown system 20 is mounted at the top of the housing 11 in order to make any large scale separation adjustment which may be necessary before or between mill operations. This system includes the usual drive motor 21 along with a reduction gear system 22 and adjustment screws 24 which bear through a breaker block-load cell assembly 44 upon the bearing chock 18. As best seen in FIG. 2, the upper and lower chocks 16 and 18 are separated by high force adjustment actuator devices 27. These actuator devices 27 operate so as to oppose the constraining forces of the mill housing on the chocks 16 and 18 and are adapted to apply force differentials upon the chocks 16 and 18 in order to maintain uniformly the output product thickness of the mill stand 10.

The compressive forces exerted by the work rolls 13 and 14 upon the strip or work product are transmitted by the adjustment screws 24 through the breaker block-load cell assembly 44, upper bearing chock 18, upper backup roll 15, and upper work roll 14 to the strip and through the housing 11 by way of nut 30 to the rocker plate 31, lower bearing chock 16, lower backup roll 12, and lower work roll 13 to the strip.

In the practice of the invention, the no-load gap or work roll separation is initially set by means of adjustment screws 24 to provide a greater than normal reduction in the thickness of a product of predetermined properties. Thereafter, the mill stand 10 is prestressed by means of force actuators 27 to achieve a normal reduction in such a product. It is possible to make perturbation adjustments in accordance with commands from an outside

source so as to maintain the work roll separation and thereby provide an output of uniform thickness from mill stand 10 irrespective of changes in the product.

The following analysis is directed to the development of an equation, which when the actuators 27 respond in accordance therewith, can enable mill stand 10 to provide a work product of constant output thickness regardless of the variations in the incoming temperature, thickness or metallurgical property of the metal product being rolled from the predetermined properties.

The preset roll separation (S) of the mill stand 10, as initially adjusted and measured by means of adjustment screws 24 to produce an output product with a desired thickness h , can be expressed in terms of Hooke's Law by an equation of the form:

$$S = h - \frac{P}{M} \quad (1)$$

wherein P is the roll separating force, which is equal to the compressive force required to reduce the strip to its required output thickness, and M is the elastic modulus of the mill stand 10.

Equation 1 is, of course, only true when the control force F_C exerted by actuators 27 is equal to zero. When a preset value of control force F_{co} is applied to the mill stand 10 prior to threading but subsequent to preselection of the values S and h , Equation 1 becomes:

$$S = h - \frac{P}{M_F} - \frac{P}{M_R} - \frac{2F_{co}}{M_F} \quad (2)$$

wherein M_F is the elastic modulus of the mill stand, neglecting the effects of the mill rolls, and M_R is the elastic modulus of the mill rolls.

When the incoming product varies in a manner to cause a change in the stand separating force (ΔP) which causes variations in the thickness of the output product (Δh), the effect may be described in the following manner by transposing terms and substituting in Equation 2:

$$S + \frac{2F_{co}}{M_F} + \frac{P + \Delta P}{M_R} + \frac{P + \Delta P}{M_F} = h + \Delta h \quad (3)$$

Inasmuch as the thickness of the output product h is to be kept to a uniform dimension, Δh must be reduced to zero, which can be accomplished by varying the value of F_C . Therefore, by inspection of Equation 3 it follows that:

$$S + \frac{2(F_{co} + \Delta F_C)}{M_F} + \frac{P + \Delta P}{M_R} + \frac{P + \Delta P}{M_F} = h \quad (\text{a constant}) \quad (4)$$

wherein, as stated, F_{co} is the initial force (chosen at a value which will permit a satisfactory range of adjustment) applied by the actuators 27. The position of adjustment screws 24 is kept constant such that S is a constant. Therefore:

$$\frac{2\Delta F_C}{M_F} = -\left(\frac{\Delta P}{M_R} + \frac{\Delta P}{M_F}\right) = -\Delta P \frac{M_F + M_R}{M_F M_R}$$

and

$$2\Delta F_C = -\Delta P \left(1 + \frac{M_R}{M_F}\right) \quad (5)$$

From FIG. 2 it is apparent that:

$$2F = 2F_C + P \quad \text{and} \quad 2\Delta F = 2\Delta F_C + \Delta P$$

wherein F_C equals $F_{co} + \Delta F_C$ and F is the force constrained at any time in the mill stand housing and equals $(F_0 + \Delta F)$ where F_0 is a selected initial or reference value for F . Therefore solving for ΔP :

$$\Delta P = 2(\Delta F - \Delta F_C) \quad (6)$$

and substituting for ΔP in Equation 5 and solving for ΔF_C :

$$\Delta F_C = (\Delta F_C - \Delta F) \left(1 + \frac{M_F}{M_R}\right) \quad (7)$$

The significance of expression (7) is that it relates the change ΔF (from value F_0 which is induced at any time in the mill stand force F to the change ΔF_C (from value F_{c0}) needed to be made at that time in the actuator force F_C in order to maintain the output product thickness of the desired value h or to restore such thickness to that value h .

The actuators 27 located between bearing chocks 16 and 18 are shown in this embodiment as hydraulic cylinders provided with fluid lines 35 and 36 for delivering from a unit 40 a supply of hydraulic fluid originally derived from a source of pressurized fluid (not shown). The fluid flow and pressure in the lines 35 and 36 are controlled by the hydraulic control unit 40 which contains a conventional electro-hydraulic servo valve such as Model 324 manufactured by Sanders Associates, a transducer for sensing pressure in the actuators such as Model PG707TC manufactured by Statham Corporation (said pressure being a measure of the force F_C exerted by the actuators); and the usual manifold, stop valves, check valves, and filters. The unit 40 is responsive to a control signal produced by amplifier 41 to adjust the force F_C exerted by the actuators 27.

In order to apply the above derived Equation 7 to control the force differential ΔF_C , exerted by the actuator devices 27, a representative control system has been set forth in FIG. 1. The various components of this system are shown in their inactive or de-energized condition. In operation, the mill adjustment screws are preset in accordance with the rolling schedule. Prior to threading the strip into the mill, contacts 1R-1 of relay 1R maintain the output of an integrator circuit 42 at 0 volt. Also, the contacts 3R-3 of relay 3R ground the shown $-\Delta F_C$ input to error sensing difference amplifier 41 to maintain that input at 0 volt.

When the product begins to thread between the work rolls 13 and 14, the force (F) constrained by the mill housing 11 increases and is measured by a conventional load cell (not shown) in breaker block-load cell assembly 44, the cell providing an input to an amplifier 45. The other input to amplifier 45 is supplied from an adjustable voltage source 45a and is representative of the initial force F_{c0} exerted by the actuators 27 upon the chocks 16 and 18. Source 45a may be adjusted in accordance with an indication derived from unit 40 of the force F_{c0} to provide a signal $-F_{c0}$ of the proper value. As represented by its negative sign, the signal $-F_{c0}$ is in voltage opposition to the signal representative of the force F .

In operation, as the strip threads between the work rolls 13 and 14 and the force F increases to increase in a positive direction the value of the combined signal input ($F - F_{c0}$) to amplifier 45, that amplifier is adapted to provide a negative output voltage of increasing magnitude such that, when the output reaches a predetermined magnitude equal to a positive bias level set into a signal comparator 1SC, the comparator 1SC energizes and closes its contacts 1SC-1 which energize relays 1R and 2R. Relay 1R, thereafter, opens its contacts 1R-1 to remove the short across the integrating capacitor 42a of the integrator 42. At the same time, relay 1R closes its contacts 1R-2 and 1R-3 to complete circuits to both of two inputs to an amplifier 46. Relay 2R is an adjustable time delay relay to permit selection of the time of activation of the system after the metal has entered the mill stand.

The output of integrator 42 is connected to an amplifier 47 of which part of the output is fed back through lead 47a through contacts 1R-3 to one of the inputs of amplifier 46. Amplifiers 46 and 47, in combination with the integrator 42, thus form a closed loop circuit adapted to develop at the output of amplifier 47 a signal which is representative of a fixed reference value for the force F . Such reference value is designated as F_0 and is used to permit the continuous solution of Equation 7 while the total length of strip is being rolled.

When signal F_0 is equal in magnitude to the signal F , a signal comparator 2SC is energized and closes its contacts 2SC-1, which causes relay 3R to be energized when the time-delayed contacts 2R-1 close. Relay 3R then opens its contacts 3R-4 to lock in the value of F_0 produced by the integrator 42 and, at the same time, opens its contacts 3R-3 to remove the short to ground for the $-\Delta F_C$ input to the amplifier 41. Relay 3R also closes its contacts 3R-1 and 3R-2 to permit the signal $-F_{c0}$ and the signal representative of the force F to be supplied to the shown amplifier 48.

The amplifier 48 operates to subtract F_{c0} from F and provides an output representative of $-\Delta F$ to amplifier 49. The output of amplifier 49 is supplied to a coefficient 15 potentiometer 51 which, in effect, multiplies that output by

$$\left(1 + \frac{M_F}{M_R}\right)$$

20 The output of unit 51 is in turn fed back through amplifier 50 to the input of amplifier 49. By standard operational amplifier techniques the circuit 49, 51, 50 solves the foregoing expression (7) to yield at the output of element 51 a signal $-\Delta F_C$ representative of the left hand term ΔF_C of that expression. As stated, ΔF_C is the change needed (from F_{c0}) in the actuator force F_C in order to maintain the output product thickness of the desired value h .

25 The amplifier 41 has supplied thereto three inputs, the first supplied over lead 52 from unit 40 and representative of the force F_C , the second from source 45a and representative of $-F_{c0}$, and the third from element 51 and representative of $-\Delta F_C$. Amplifier 41 sums those three inputs to supply over lead 53 to control unit 40 an error signal E which is a function of the quantity $(F_C - F_{c0} - \Delta F_C)$. The primary function of amplifier 41 is to control unit 40 so as to maintain the total actuator force F_C at the value $F_{c0} + \Delta F_C$ needed to yield the desired value h for the output product thickness. By performing that function by means of the shown closed loop connected of units 40 and 41 (wherein the signal F_C is derived from unit 40 and fed back to unit 41), the additional advantage is realized that the actual value F_C of the actuator force is prevented by the closed loop circuit from departing significantly from the value $F_{c0} + \Delta F_C$ commanded for that force.

30 In operation, the system shown in FIG. 1 is arranged to rapidly adjust for variations in the incoming product by solving Equation 7 and, in accordance therewith, by varying the force exerted by the actuators 27 (acting in unison) to maintain a uniform output product. It is to be particularly noted that the present invention does not require the use of any gages to measure the product entering and leaving the mill stand 10.

35 It will be understood by those skilled in the art that the above-described embodiment is meant to be merely exemplary in that it is susceptible to modification and variation without departing from the spirit and scope of the invention. For example, the invention has been illustrated in regard to a four-high rolling mill, but its applicability with other types of mill stands will be readily appreciated by those skilled in the art.

40 Further, the signal ΔF_C can be derived from circuits simulating the expression:

$$\Delta F_C = \left(1 + \frac{M_R}{M_F}\right) \Delta F \quad (8)$$

45 which is equivalent to the foregoing expression (7). Still further, the shown closed loop of units 40 and 41 can be replaced by an open loop connection wherein the signal supplied over lead 53 is proportional to the desired total actuator force ($F_{c0} + \Delta F_C$) and commands the control unit 40 to cause each actuator 27 to yield that force.

50 Therefore, all such variations and modifications are included within the scope of the invention as set forth in the appended claims.

I claim:

1. In a rolling mill having a plurality of rolls rotatively mounted about substantially parallel axes, bearing means for supporting the rolls, means supporting the bearing means for constraining the separating force imparted to the rolls by the product being rolled, means mounted on the supporting means and acting on at least one roll to set the separation between the rolls, adjustable actuator means acting on the bearing means to apply a force which coacts with the separating force to oppose the force constrained by the supporting means, the actuating means including means responsive to a control signal to vary the force applied thereby, the control signal being a function of the force constrained by the supporting means to maintain the work roll separation, wherein the varying force ΔF_C , applied by the adjustable actuating means satisfies the relationship:

$$\Delta F_C = (\Delta F_C - \Delta F) \left(1 + \frac{M_F}{M_R} \right)$$

wherein ΔF is the differential in force constrained by the supporting means and M_R and M_F are, respectively, the elastic modulus of the mill rolls and the elastic modulus of the mill stand neglecting the effects of the mill rolls.

2. In a rolling mill as in claim 1 wherein the actuator varying means includes high force hydraulic actuators, a source of pressurized fluid, and system means for controlling the pressure of the fluid admitted to the actuators.

3. In a four-high rolling mill for producing a product of substantially uniform output thickness having a fixed housing, a roll assembly including upper work and backup rolls, lower work and backup rolls, all of the assembly rolls mounted about substantially parallel axes, upper

bearing means mounted on the housing for supporting the upper rolls, lower bearing means mounted on the housing for supporting the lower rolls, means mounted on the housing and acting on at least one roll to set the separation between the work rolls, a plurality of high force actuators each acting in unison on the upper and lower bearing means to provide a force thereon, and means for varying the force applied by the actuators to satisfy the relationship:

$$\Delta F_C = (\Delta F_C - \Delta F) \left(1 + \frac{M_F}{M_R} \right)$$

wherein ΔF is the differential in force constrained by the housing and M_R and M_F are, respectively, the elastic modulus of the mill rolls and the elastic modulus of the mill stand neglecting the effects of the mill rolls.
